WHIRLPOOL BATH ATTACHMENT

Donald W. Doman, Janesville, Wis., assignor to Kohler Co., Kohler, Wis.

Filed Dec. 21, 1970, Ser. No. 26,584

Term of patent 14 years

Int. Cl. D24—04

U.S. Cl. D83—1

Fig. 3

Fig. 5

FIG. 1 is a side view in elevation of a whirlpool bath attachment showing my new design and the broken line representation is for illustrative purposes of indicating environmental structure.

FIG. 2 is a front view in elevation of the whirlpool bath attachment,

FIG. 3 is a rear view in elevation of the whirlpool bath attachment,

FIG. 4 is a top plan view of the whirlpool bath attachment, and

FIG. 5 is a bottom plan view of the whirlpool bath attachment.

I claim:

The ornamental design for a whirlpool bath attachment, as shown and described.
